HEAT UTILIZING COVERING FOR STOVE PIPES

August B. Wolbers, Pittsburgh, Pa.

Application April 13, 1933, Serial No. 665,969

On April 1

My invention relates to improvements in heaters for the purpose of utilizing radiated heat from a stove pipe or other products of combustion conduit. It is particularly adapted to application to domestic heaters, such as household stoves, which are used with solid or gaseous fuel for heating of residences or other buildings. In modern practice, it is somewhat usual to surround the ordinary domestic stove with an ornamental 5 casing, from which the conventional stove pipe usually passes upwardly through a room for connection to a flue at a higher level.

In my invention I provide a surrounding preferably ornamental shell, as hereinafter described, adapted if desired to conform to the style, ornamentation, color, etc. of the main stove covering, and to conceal the usual stove pipe between the stove and the flue connection. The principal useful function of such covering however, is to provide between it and the stove pipe a surrounding circulating channel for additional heating and distribution of the heated air in a room, hallway, or the like.

25 Certain preferred embodiments of the invention are illustrated in the accompanying drawings, in which:

Fig. 1 is a view in elevation showing a continuous outlet stove pipe provided with my improvement;

30. Fig. 2 is an enlarged cross sectional view on the line II-II of Fig. 1;

Fig. 3 is a perspective detail view showing adjacent connecting corner portions of the sectional

covering;

35 Fig. 4 is a perspective detail view, partly broken away, showing the supporting means between the stove pipe and the surrounding air circulating and distributing wall members;

Fig. 5 is a perspective detail view of the blank 40 from which the supporting bracket is made;

Fig. 6 is a detail view showing the upper elbow member for the outlet end of the stove pipe;

Fig. 7 is an end view thereof; Fig. 8 is a view similar to Fig. 3, showing a

Fig. 9 is a collective separated perspective view showing portions of the straight and elbow sections respectively in adjacent positions.

Referring to the drawings, A represents the
main heater as a stove provided with the ornamental

mental outer casing *a*, when used, and having the terminal outlet pipe connection *2*.

The usual stove pipe construction utilizes an elbow joint member 3 and one or more sections 4 of a straight stove pipe, connected in the usual manner and provided at the upper end with an outlet elbow 5, communicating with the flue 6, as in Fig. 1. The straight sections of the stove pipe are covered with enclosing casing sections B, and the elbow joints 3 and 5 are covered with the correspondingly shaped casing sections C, constructed as hereafter described.

The sections B are made of two generally angle-shaped pieces of comparatively thin sheet metal, bent at their middle to provide a corner 7 extending rectangularly therefrom, providing the diverging walls 8-8. Such angle-shaped sections are of suitable length and adapted to make abutting engagement with each other, or are preferably bent inwardly at one end, as at 9, to make sliding telescoping engagement with the opposite end of the next section, as in Fig. 3.

Each such section, when brought together around the stove pipe, with another similar section, thereby provides a complete box-like enclosing casing or shell, with ample intervening space between it and the stove pipe 4 for upward circulation of air continuously around and between the stove pipe and such casing. 2

For the purpose of fixedly supporting and holding the box-like sections in such spaced relationship, I utilize a series of clamping bands 10 of thin sheet metal, held together by securing screws or bolts 11 through terminal flanges 12. Each band 10 is continuous and of the proper length to embrace the stove pipe of any definite diameter, with sufficient clearance for tightening and permanent clamping engagement.

conform to the complete length of the stove pipe in application.

Screws 13 connect the outer shell sections with the vertical bracket walls 15 having receiving screw holes 16, as in Fig. 4, for such attachment. The supporting brackets D are made of thin sheet metal from the blank shown in Fig. 5, having the middle inwardly extending tongue 17 adapted to be bent downwardly at right angles on the dotted line and secured to band 10 by rivet 18.

The side wing portions 15 are similarly bent downwardly on the dotted lines 19, the end portions of the blank being deflected inwardly as at 20. The terminals of the blank are provided with the inwardly extending ears 21 which are bent downwardly on the dotted line, with slight intervening space, providing the supporting stirrup or bracket terminals, adapted to embrace and engage the upper edge portion of the band 10, as in Fig. 4.

When thus located, one at each opposite side of the band, the brackets provide rigid outwardly extending bases for attachment of the outer shell sections. Each complete section B is thus maintained in position, and forms a completely covering outside casing wall surrounding the main straight portions of the stove pipe.

At one or both ends, where necessary, the stove pipe elbow sections C are located, forming flush continuations of the sections B, between them and the main stove A, and with the outlet flue connection below and above respectively.

Sections C are generally similar to sections B except that they are usually made of quarter round form, as in Figs. 1, 6 and 9, conforming to the general contour of the stove pipe elbow. In such case the elbow casing is formed of two angle-shaped members, one having the outer large radius wall 22 and the flat side wall 23, the other side having the inner small radius wall 24 and the flat side wall 25. The elbow sections may be rectangular in cross section, like the straight sections, and are connected to and supported by a pair of double bracket bands 10 of the same construction as above described, as in Figs. 6 and 7. The ends of the sections B and C preferably overlap or underlap, and when assembled provide a continuous outer box-like casing, continuously spaced away from the stove pipe from one end to the other.

Each of the several sections is provided with perforating circulation openings 26 through some or all of the four sides of the complete conduit. Openings 26 may be in any desirable arrangement and varied in configuration or design to assume different ornamental outlines or shapes, the main function however being to provide outlet circulation openings for heated air from the enclosed space between the stove pipe and its covering.

The lower elbow section C is preferably provided with an opening 27 at its under side, into which cold or normal air will pass when the stove pipe is hot, circulating upwardly around the pipe and outwardly through the openings 26 throughout its length to the top. It will be understood however, that incoming cool air at the base of the covering casing may be admitted through the lower ventilating openings, circulating outwardly there-through as the air rises in temperature upwardly.

I show in Fig. 8 a modified construction for either straight or elbow sections of stove pipe. The sections 8a are of approximately semi-cylindrical form, providing a substantially annular air circulation space between them and the stove

pipe. In such case the brackets D are formed to provide the continuously rounded vertical faces 15a conforming to the contour of the sections, with effective spacing adjustment. The brackets and sections are similarly connected by screws and are otherwise substantially the same as in the rectangular form, above described.

The construction and operation of the invention will be readily understood from the foregoing description. It may be applied to any existing stove pipe by application of the successive pairs of bands 10, which are amply flexible to permit opening around the pipe by removal of the nuts of screws or bolts 11, then bringing the ends together and tightening them in place. The successive outer sections are then applied, so that the entire pipe becomes covered.

The covering casing provides not only a useful heat utilizing medium, but also conceals the usually black and unsightly stove pipe and presents a covering therefor which may be decorated in harmony with the general design, color, etc. of the stove itself or its ornamental casing. Obviously the device may be enameled or otherwise colored in various shades to adapt it to such standard color scheme, or otherwise effect harmony in color, design, etc. of the room or apartment.

The device is comparatively simple, made of any suitable sheet metal or material, economical to manufacture and install, and may be applied without the necessity of skilled labor. Obviously it may be varied or changed in dimensions, detail construction, ornamentation, or otherwise by the skilled mechanic, within the scope of the following claims.

What I claim is:

1. In combination with a stove pipe, an enclosing double-section longitudinally divided perforated covering, and movable clamping means on the stove pipe having flat faced brackets supporting and connecting the sections together in outwardly spaced relation on the stove pipe.

2. In combination with a stove pipe, an enclosing separable clamping band, provided with terminal bolt connected flanges and a pair of oppositely arranged outwardly extending flat faced brackets, and an outwardly spaced longitudinally divided covering of perforated sheet metal, the sections thereof having their longitudinal meeting edge portions connected with the brackets.

3. In combination with the elbow section of a stove pipe, an enclosing double-section covering, one section having a flat side and an outwardly rounded connecting wall, the other section having a flat side and an inwardly rounded connecting wall, and means supporting the sections in outwardly spaced relation to the elbow section.

4. In combination with the elbow section of a stove pipe, an enclosing double-section covering, one section having a flat side and an outwardly rounded connecting wall provided with an air inlet opening, the other section having a flat side and an inwardly rounded connecting wall, and means supporting the sections in outwardly spaced relation to the elbow section.

5. In combination with the elbow section of a stove pipe, an enclosing double-section covering, one section having a flat side and an outwardly rounded connecting wall, the other section having a flat side and an inwardly rounded connecting wall, and separable clamping bands on the elbow section having outwardly projecting brackets connected with said sections.

6. Means providing an air heating covering for

5 a stove pipe consisting of a flexible clamping band and means for holding it in position, oppositely located brackets extending laterally of the band having screw holes, and an outer covering consisting of sheet metal sections outwardly spaced around the band having meeting edge portions and screw holes, and screws extending there-
through and engaging the bracket holes.

10 7. Means providing an air heating covering for a stove pipe consisting of a flexible clamping band

and means for holding it in position, oppositely located brackets extending laterally of the band having screw holes, and an outer covering consisting of sheet metal sections outwardly spaced around the band having meeting edge portions and screw holes and ventilating openings there-
through, and holding screws connecting the sec-
tions with the brackets. 5

AUGUST B. WOLBERS. 10
